UNITED STATES PATENT OFFICE.

LEON H. CLARK, OF PHILADELPHIA, PENNSYLVANIA.

CHAIR.

SPECIFICATION forming part of Letters Patent No. 740,531, dated October 6, 1903.

Application filed July 19, 1902. Serial No. 116,143. (No model.)

To all whom it may concern:

Be it known that I, LEON H. CLARK, a citizen of the United States, residing at Philadelphia, in the county of Philadelphia and State of Pennsylvania, have invented certain new and useful Improvements in Chairs, of which the following is a specification.

My invention relates to improvements in that class of chairs having hinged or movable backs commonly known as "reclining-chairs;" and it consists in devices for shifting the rod from the notches which support the back without stooping to raise the same, so that the inclination of the back may be adjusted by simply moving the same forward and backward in a manner hereinafter fully described.

Referring to the accompanying drawings, forming part of the specification, Figure 1 illustrates a side elevation of a chair embodying my invention, and Fig. 2 illustrates a rear elevation of the same.

Referring to the reference-letters of the drawings, A represents the base or body of the chair, and B the movable back, which is hinged in a suitable manner at points B'. At the sides of the chair-body are secured brackets C C, each of which has two arms, one of which is provided with a number of projecting teeth forming a series of notches c for the reception of a rod or bar E and with a curved end c' to release the bar. The other arm, C', projects upwardly and is slightly curved.

Fastened to the back B of the chair are arms D D, each having at the top a slotted opening d to receive the rod E.

The function which the above-mentioned parts perform is as follows: When the back B is in the position shown in Fig. 1 and it is desired to give it less incline, the back is moved forward. The arm D will carry the rod E up the incline, and it will fall into one of the notches c in advance of the one it at present occupies and will continue to so act until the rod has reached the inclined end c', when the rod is thrown backward into the slotted end d of the arm D, which releases

the rod from engagement with the toothed portion of the bracket C and allows the back of the chair to be moved in the opposite direction until the projecting ends of the rod E come in contact with the arm C' of the bracket C, and a further movement of the back of the chair in the same direction will release the rod E from the slots d and return the rod to the position shown in Fig. 1.

Having described my invention, what I claim, and desire to secure by Letters Patent, is—

1. The combination in a chair of the body, a movable back, notched brackets secured to the body, a rod adapted to engage the notches in the brackets, notched arms secured to the back adapted to move said rod forward and backward, and arms projecting from the brackets adapted, upon the backward movement of the back, to engage and release said rod from the notches in said notched arms.

2. The combination in a chair, of a body portion, a movable back, notched brackets secured upon the sides of the back of the body portion, a movable rod adapted to engage the notches in said brackets successively, means, carried by the movable back, for carrying said rod, upon an upward movement of said back, from a lower to a higher set of notches, means carried by said back for engaging said rod and lifting it from the upper notches in said brackets, and means carried by the body portion of said chair for disengaging said rod from said engaging and lifting means and for returning it to the bottom of said notched brackets upon a backward movement of said back.

3. A reclining-chair comprising a body portion, brackets secured thereto each having two projecting arms, one arm of which is provided with notches and with a curved end, a hinged back, arms fastened to the back each having a slotted end, a rod extending across the back of the chair and carried by said arms, the ends of the rod being adapted to enter the notches of the brackets and to be

carried by the arms so as to register with the several notches of the brackets when the back is moved forward, to be released from engagement with the brackets when moved to the extreme limit of its forward movement, and brought into engagement with the slotted ends of the arms of the back, and to be released from the slotted ends of said arms and

returned to engagement with the bracket when moved in the opposite direction. 10

In testimony whereof I affix my signature in presence of two witnesses.

LEON H. CLARK.
